UNITED STATES PATENT OFFICE.

EDWARD T. LEWIS, OF LOS ANGELES, CALIFORNIA.

ALARM-CLOCK.

1,245,245.

Specification of Letters Patent.

Patented Nov. 6, 1917.

Application filed March 28, 1917. Serial No. 158,026.

To all whom it may concern:

Be it known that I, EDWARD T. LEWIS, a citizen of the United States, residing at Los Angeles, in the county of Los Angeles and 5 State of California, have invented new and useful Improvements in Alarm-Clocks, of which the following is a specification.

This invention relates to an alarm clock and particularly pertains to winding means 10 for winding the time-mechanism and the alarm-mechanism.

In alarm clocks of common construction the alarm-mechanism is usually wound by one key while the timing-mechanism is 15 wound by another key. It is the principal object of this invention to provide simple means for permitting the alarm and timing-mechanism to be wound by the same key, either simultaneously or separately.

20 Another object of this invention is to provide means whereby the alarm-mechanism will remain idle while the timing-mechanism is wound, without damaging the spring of either the alarm or timing-mechanisms.

25 It is a further object of this invention to provide a winding key and a mechanism actuated thereby which are simple in construction, will eliminate the use of a number of parts now necessary in most alarm clocks, 30 and may be easily operated to produce the desired results.

Other objects will appear hereinafter.

The invention is illustrated, by way of example, in the accompanying drawings in 35 which:

Figure 1 is a view of an alarm clock as seen in rear elevation with parts of the case broken away to disclose the winding mechanisms of the alarm and time movements.

40 Fig. 2 is a view in section and elevation disclosing the positions of the main spring and the alarm spring and illustrating in detail the winding gears connected therewith.

Fig. 3 is a view in end elevation as seen 45 on the line 3—3 of Fig. 2 illustrating the clutch action of the alarm mechanism spring.

Fig. 4 is a view in elevation disclosing a modified form of the invention.

Referring more particularly to the drawings, 50 10 indicates the case of an alarm clock, which is here shown as provided with a clock mechanism 11 and an alarm-mechanism 12. The clock mechanism is adapted to be driven by a main spring 13 while the alarm-mechanism is driven by a coil spring 14. The 55 spring 14 is secured at its inner end to a

winding shaft 15 around which it is coiled. The outer end of the spring 14 is loosely confined within a circular spring drum 16. This drum is mounted upon the back of a 60 driving gear 17 adapted to impart motion to the alarm-mechanism. The tendency of the spring 14 to expand itself causes the free end thereof to frictionally engage the inner periphery of the drum and drive the 65 gear. An ordinary clock spring will run an alarm much longer than is desired, and so by using one of these long springs in the alarm drum I am able to get sufficient action out of the alarm and leave several 70 turns of the spring unwound against the inner face of the drum, and this serves as a friction drive. When too much of the spring is wound it will slip in the drum but as soon as the winding stops 75 the spring will clutch the drum again. Fixed at the outer end of the shaft 15 is a winding gear 18 which is here shown as in constant mesh with a winding pinion 19. This pinion is secured upon a short stub-shaft and 80 is interposed between the alarm winding gear 18 and the timing-mechanism winding gear 20. As shown in Fig. 1 of the drawings, this pinion is in mesh with both gears 18 and 20. Reference being had to Fig. 2, 85 it will be seen that the gear 18 is of greater thickness than the gear 20 and also that the pinion 19 is slidably mounted upon the stub-shaft. By drawing outwardly upon the key 21 the pinion may be drawn from 90 mesh with the gear 20 and, due to the thickness of the gear 18, will remain in mesh therewith so that the alarm-mechanism may be wound independent of the timing-mechanism. A spring 22 is positioned upon the 95 outer end of the stub-shaft and yieldably holds the pinion 19 in mesh with both gears 18 and 20.

In the modified form of the invention, as disclosed in Fig. 4 of the drawings, it will 100 be seen that the winding pinion 19 is mounted upon an oscillating arm 23 and is in mesh with the gear 20 and may be swung into mesh with gear 18 and it may be rotated by the key 21.

105 In operation, the two mechanisms are wound by turning the key 21. In case the alarm spring 14 is wound before the winding of the main spring 13 is completed, the spring 14 will slip within the drum 16 and 110 will permit the shaft 15 to rotate without damaging the spring. At the same time,

however, the main spring may be continuously wound, as will be understood. In case the main spring has been wound and it is desired to wind the alarm-mechanism, the key 21 is drawn outwardly and the pinion slipped from mesh with the gear 20, after which it may be rotated to wind the spring 14 independently.

In the modified form, the two springs may be wound simultaneously by swinging the pinion 19 into mesh with gears 18 and 20, the winding action being the same as previously described, and when the main spring is to be wound separately the pinion may be swung out of mesh with the gear 18 and will continue in mesh with the gear 20. In using this modified form, if it is desired to wind the alarm spring, care should be taken to throw the pinion 19 into mesh with the gear 18 before the main spring has been wound.

It will thus be seen that the winding device here provided is simple in its operation and construction and will positively produce the results desired.

While I have shown the preferred construction of my alarm clock as now known to me, it will be understood that various changes in the combination, construction, and arrangement of parts may be made by those skilled in the art without departing from the spirit of my invention.

I claim:

1. In an alarm clock, the combination with a time-mechanism, of an alarm-mechanism, a coiled spring operating said time-mechanism, a coiled spring operating said alarm-mechanism, and a single means at the will of the operator for selectively winding either the spring for said alarm-mechanism or both of said springs simultaneously.

2. In an alarm clock, the combination with a time-mechanism, of an alarm-mechanism, a coiled spring operating said time-mechanism, a coiled spring operating said alarm-mechanism, and means for winding said springs simultaneously, said means comprising a shaft, a winding pinion loosely

mounted thereon, manually operated means for rotating said pinion, a winding gear wheel operatively connected to the spring 50 for said time-mechanism, and a gear wheel operatively connected to the spring of said alarm-mechanism, both of said gear wheels being in mesh with said pinion and said pinion being adapted to move out of mesh 55 with one of said gear wheels.

3. In an alarm clock, the combination with a time-mechanism, of an alarm-mechanism, a coiled spring operating said time-mechanism, a coiled spring operating said alarm-mechanism, each of said springs having a separate gear wheel operatively connected thereto, said gears being disposed in the same plane, a driving pinion in mesh with both of said gear wheels, means for rotating, 65 said pinion to wind said springs, a shaft on which said pinion is loosely mounted, and resilient means tending to hold said pinion in mesh with both of said gear wheels and means whereby said pinion may be moved, 70 out of mesh with one of said gear wheels.

4. In an alarm clock, the combination with a time-mechanism, of an alarm-mechanism, a coiled spring operating said time-mechanism, a coiled spring operating said alarm-mechanism, separate gear wheels operatively connected to said springs, a winding pinion in mesh with both of said gear wheels, manual means for rotating said winding pinion, a barrel in which the spring 80 for said alarm-mechanism is coiled, and a shaft on which the gear wheel for said alarm spring is mounted, said shaft extending into said barrel and being permanently attached to the inner end of said alarm spring, said 85 alarm spring being of a length to sufficiently fill said barrel and having its outer end unattached, whereby the pinion may wind the gear wheel for the alarm spring continuously without danger of breaking said 90 last named spring.

In testimony whereof I have signed my name to this specification.

EDWARD T. LEWIS.
